UNITED STATES PATENT OFFICE

HOWARD L. BUDD, OF BROOKLYN, NEW YORK, ASSIGNOR TO FRIEDMAN SILVER CO., INC., OF BROOKLYN, NEW YORK, A CORPORATION OF NEW YORK

PICTURE FRAME

Application filed May 20, 1929, Serial No. 364,356.

This invention relates to ornamental frames of the type adapted to hold a picture removably, and to rest on an article of furniture or to hang on a wall, and designed to present an ornamental appearance.

In frames of this type, the frame proper or body is usually made of metal, L-shaped in cross-section. A back supported by an easel or designed to be hung up, as on a wall, is inserted into the frame for the purpose of holding the glass and picture in proper position. The back is usually made of wood, cardboard and comparatively inexpensive composition board of various types, and is often completely covered with velvet or other ornamental material cemented thereto by a suitable cement or glue. Such backs, however, due to the action of the glue, cement, moisture or atmospheric conditions, may become warped and shrink or otherwise change their shape and size, resulting not only in spoiling the good appearance of the frame, but in such a poor fit of the parts that the frame members are insecurely held together with resulting danger of damage. Since such frames are used largely for ornamental purposes, a remedy seeking to prevent warping of the back has long been sought.

My invention contemplates the provision of means for so reinforcing and bracing the back that danger of warping thereof for any reason is permanently eliminated, and the parts may fit the frame properly at all times and under all normal conditions.

My invention further contemplates the provision of means for so supporting the frame of the standing type, that the bottom edge of the metallic portion of the frame does not at any time come in contact with the article on which it rests, thereby avoiding mutilation of the supporting surface.

The various objects of my invention will be clear from the description which follows and from the drawings wherein

Fig. 1 is a perspective view of an easel frame to which one form of my invention has been applied.

Fig. 2 is a similar view of the reinforced back and easel as they appear before the velvet covering has been applied thereto.

Fig. 3 is a vertical section of the lower portion of the frame, taken on the line 3—3 of Fig. 1.

Fig. 4 is a fragmentary perspective view of one corner portion of the back as it appears after it has been covered with velvet. 55

Fig. 5 is a similar view of a modified form of the same.

Fig. 6 is a rear elevational view of a modified form of a frame embodying my invention. 60

Fig. 7 is a vertical section thereof, and

Fig. 8 is a perspective view of my improved back member, showing a modified form of reinforcing means therefor. 65

In the practical embodiment of my invention which I have illustrated by way of example, the usual metallic frame is provided. As illustrated in Figs. 1 and 3, the frame 10 may be L-shaped in cross-section, being provided with the flanges 11 and 12, the exposed surface of said flanges being suitably ornamented if desired. For holding the back 13 in place, I provide a downwardly extending holding member 14 secured to the rear edge 70 of the uppermost flange 12. To the lowermost flange 12 of the frame, I secure a suitable bendable clip as 15, preferably of thin metal, and adapted to be turned upwardly into contact with the rear face of the back 75 13, and thereby to cooperate with the member 14 for holding the back securely in position.

To insert the back into the frame, the upper edge of the back is inserted in front of the member 14, the back being tilted for that purpose, after which the back is swung into position inside of the frame and the clip 15 bent upwardly from its dotted line position shown in Fig. 3 to its full line position, illustrated in said figure. 85

In its operative position, the back is held in place by the members 14 and 15, and preferably also by its frictional contact with the inner faces of the flange 12, and serves to force the picture 18 and the glass 19 firmly 90 against the inner face of the flange 11. If desired, an easel as 16 of the usual type may be hingedly secured to the back as at 17 in any suitable manner, as by means of the velvet covering, as is well known in the art. 95 100

Or the easel may be omitted, and suitable hanging members provided, as is well understood.

Both the back 13 and the easel 16 may be suitably reinforced against possibility of distortion. The means I prefer to use for this purpose consist of channel-shaped metallic members bent about the peripheral portions of the back and permanently secured in pressed contact therewith. As illustrated in Figs. 2, 3, and 4, said metallic members as 20 and 21 are preferably made of thin sheet metal conforming to the shape of the edge portion and by reason of their shape, resisting distortion of the back in all directions. The covering 22 for the back is suitably glued or cemented thereto, preferably in position outside of and concealing the metallic members 20 and 21, which if so concealed, may be made of comparatively inexpensive material.

As shown in Fig. 3, the reinforcing members 20 and 21 may be pressed into the material of the back so as to become flush or even with the surfaces thereof.

As shown in Fig. 4, however, said members 20 and 21 may merely be bent about the edge into pressed contact with the faces of the back, the covering concealing said reinforcing members.

As shown in Fig. 5, the velvet covering 22 may first be secured to the back and thereafter, the reinforcing member 23 secured about the edges of the back so as to remain substantially visible. In this case, I prefer to make said members 23 more or less ornamental, so as to enhance the pleasing appearance of the frame, which is of major importance in articles of the type to which this invention pertains. As illustrated in Fig. 8, the reinforcing member 24 may assume the form of a thin metallic sheet having one face 25 completely or substantially covering one face of the back 13 and having peripheral channel portions 26 bent about the edge of the back and on to the opposite face.

Referring now to Figs. 6 and 7, I have there shown a modified form of frame to which my invention may be applied. In this modification, the flange 12 may terminate in a lip as 27 substantially parallel to the flange 11. Said flange or lip 27 extends about the sides and top of the frame 10, and may extend about the bottom thereof also, if desired. The back 30 is therefore inserted into place by a vertical sliding movement past the narrowed horizontal flange 31 of the lowermost member of the frame, and is prevented from falling out by the lips 27. In this modification, I prefer to make the back 30 of sufficient length to extend below the lowermost flange 31 of the frame, whereby the entire device, in its operative position rests on the edge 32 of the back, so that the flange 31 and consequently, the entire frame is maintained above the supporting surface on which the device is in-

tended to rest. For allowing the clip 15 to be turned up so as to hold the back in place, I prefer to cut away the central portion of the back 30 as at 33 to form the edge 34 which is substantially in alignment with the inner face of the flange 31. 70

It will be seen that as the frame is tilted into its operative position, the edge 35 of the easel 16 rests on the supporting surface as does the edge 32 of the back, and that no part of the frame can come in contact with the supporting surface and scratch or otherwise mutilate it. 75

It will further be seen that I have provided simple and effective means, which does not detract from the good appearance of the back, for preventing warping thereof or distortion in any direction, and that I have provided simple, economical and efficient means for the purposes intended, and which are well adapted to meet the severe requirements of practical use. 80

It will be understood that while I have illustrated and described certain preferred forms of my invention, I do not wish to be understood as limiting myself thereto, but I intend to claim my invention as broadly as may be permitted by the state of the prior art and the terms of the appended claims. 85

I claim:

1. The combination with a picture frame having a back-receiving recess, of an opaque back member of material of vegetable origin subject to distortion under varying conditions of moisture and removably fitted into said recess, a glass fitted into the recess forwardly of the member, and means for preventing the distortion of the back member comprising thin sheet metal reinforcing members permanently enclosing the peripheral portions of the back member and directly engaging both faces of said member and resisting change in size and deformation in all directions, the outermost dimensions and outline of the reinforcing members being substantially the same as the dimensions and outline of the recess, and the reinforcing members being secured to the back member and forming an inseparable unitary structure therewith, substantially filling the rear part of the recess. 100

2. A supporting member for a picture frame comprising a comparatively soft, compressible, thin, flat, composition sheet normally subject to distortion, means permanently secured to said sheet against removal therefrom for resisting distortion of said sheet in all directions and for maintaining said sheet in its flat state and for maintaining the outermost dimensions of said sheet permanent, comprising bendable metallic members permanently embedded into the peripheral portions of said sheet under pressure with the major portions of the inner faces of said members arranged inwardly. 110

of the outer faces of the sheet and in direct contact with said peripheral portions, and a fabric covering cemented to said sheet, said sheet, members, and covering forming a permanent unitary structure.

3. In a picture frame, a frame member having an annular recess in the rear face thereof for the reception of a glass and a supporting member, a glass of substantially the same size as said recess, fitted thereinto, a supporting member of substantially the same size as said recess fitted thereinto rearwardly of the glass for forcing said glass toward the front of the frame, said member comprising a comparatively thin, flat, compressible composition sheet normally subject to distortion, means permanently secured to said sheet against removal therefrom for resisting the distortion of said sheet in all directions and for maintaining said sheet in its flat state and for maintaining the outermost dimensions of said sheet permanent and of substantially the size of said recess, said means comprising a bendable metallic member permanently secured under pressure to the peripheral portions of said sheet and in pressed contact with both faces thereof, and a covering secured to said sheet, said sheet, said metallic member and said covering forming a permanent unitary and inseparable structure.

4. In a picture frame, a metallic frame member, means on said member for holding a back in place, including a bendable metal clip secured to the lower rear portion of said frame, a velvet covered back of compressible material for said frame, means permanently secured to said back for bracing the edges of said back and preventing the distortion thereof comprising thin, channel-shaped, metallic members arranged about said edges under pressure and slightly embedded into the back, and a velvet covered easel hinged to the rear face of said back.

5. In a picture frame, a metallic frame member, a glass fitted into said frame, a back of compressible and distortable material for forcing said glass toward the front of said frame, means for holding said back in place including a bendable clip at the lower portion of said frame, means independent of the frame and adapted to fit thereinto for permanently enclosing and reinforcing the edges of said back against changes in size and shape and an easel hinged to said back and cooperating with said back for supporting said frame above a supporting surface.

6. In a picture frame, a frame member, a back fitted into said member and extending below said member in its operative position for preventing contact of said frame with the supporting surface therefor and a bendable metallic clip extending rearwardly from the frame, said back having a cut out por-

tion at its lower edge for the passage of said clip toward the rear of the back.

7. In a picture frame, a frame member, a back fitted thereinto, a lowermost portion on said back extending below said frame, and having a portion thereof cut away, and a bendable clip on said frame adapted to be bent into contact with the rear face of the back for maintaining said back in place.

8. In a picture frame, a metallic frame member substantially rectangular in outline, means extending inwardly from the rear edge of said frame member for guiding a back member into operative position in the frame and for holding said back member in place, including a bendable clip extending rearwardly from the lower part of said frame member, a back member inserted into said frame and of sufficient length to extend slightly below said frame, said back member being cut away at its lower edge for allowing the passage of said clip past the cut away portion, a glass interposed between the back member and the front of the frame member and pressed by said back member against said front, an easel hinged to said back member and cooperating therewith to support the frame member above a horizontal supporting surface, a velvet covering for said back member and said easel, cementitious material securing said cover to said back member and said easel, a channel-shaped, thin metallic member secured to and enclosing the edge of said back member for resisting distortion of said back member, and a similar metallic member for said easel.

9. In a picture frame having a rear annular recess therein, a comparatively soft, distortable, and compressible member, and distortion preventing means for said member of substantially the same size and shape as said recess adapted to be removably fitted into the recess and comprising a metallic member pressed toward and enclosing an edge portion of said supporting member and in pressed contact therewith to form a permanent inseparable edge closure therefor and a unitary structure therewith.

10. In a picture frame, a metallic frame member substantially rectangular in outline, a back member inserted into said frame member and of sufficient length to extend slightly below said frame member, means extending inwardly from the rear edge of said frame member for holding said back member in place, including a bendable metallic clip extending rearwardly from the lower part of said frame member, said back member being cut away at its lower edge for allowing the passage of said clip past the cut away portion, a glass interposed between the back member and the front of the frame member and pressed by said back member against the front, a velvet covering for said back mem-

ber, and cementitious material securing said cover to said back member.

11. In a picture frame, a metallic frame member including a front flange and a side flange extending rearwardly from the front flange and substantially at right angles thereto to provide a back-receiving recess, a metallic bendable clip secured to one of said flanges and extending rearwardly therefrom and arranged with the front part thereof in said recess, a substantially rigid back member of comparatively soft distortable and compressible material fitted into said recess and adapted to engage the side flanges of the frame, means for maintaining the outer dimensions of said back member against change and for preventing distortion of said back member under varying conditions of moisture comprising a channel-shaped thin metallic member having the flanges thereof pressed toward and enclosing an edge portion of the back member to form a permanent closure therefor and a unitary structure therewith and a fabric covering for said back member, said clip being adapted to have its rearmost portion bent parallel to the front flange and into contact with the rear face of the back member to hold said back member against movement out of said recess.

12. The combination with a picture frame having a rear annular recess therein, of a supporting member, made of paper composition and substantially rigid while having the inherent tendency to change its size and shape under varying conditions of heat and moisture, means for overcoming said tendency comprising a metallic binding strip for the edge portion of said sheet forming a permanent inseparable closure for said edge portion and forming a unitary structure therewith, the outermost dimensions and shape of said strip being substantially the same as the dimensions and shape of said recess to substantially fill the rear part of said recess and to permit the member to be inserted into and removed from the recess for changing the contents of the frame.
